UNITED STATES PATENT OFFICE.

CLARK H. LANDIS, OF BOWLING GREEN, OHIO.

AUTOMOBILE-SIGNAL.

1,383,312.

Specification of Letters Patent.

Patented July 5, 1921.

Application filed October 30, 1919, Serial No. 334,441. Renewed March 10, 1921. Serial No. 451,331.

To all whom it may concern:

Be it known that I, CLARK H. LANDIS, a citizen of the United States, residing at Bowling Green, in the county of Wood and State of Ohio, have invented certain new and useful Improvements in Automobile Signals; and I do declare the following to be a full, clear, and exact description of the invention, such as will enable others skilled in the art to which it appertains to make and use the same.

This invention relates to automobile signals.

One object of the invention is to provide an improved signal in which a plurality of lighted compartments combine to produce conventional representations of arrows and combinations of parts of arrows by the use of lights and appropriate light regulating means.

A further object is to provide a device of this character in which the signs are relatively large and distinct, consistent with the relative smallness and compactness of the 25 device which comprises the signs.

A further object is to provide an improved device of this character which is exceedingly convenient, practical, durable and efficient, and can be manufactured at a comparatively 30 low cost.

Other objects and advantages may become apparent to the persons who read the following details of description in connection with the accompanying drawings in which:

Figure 1 is a perspective view illustrating the complete device ready for attachment to an automobile and to a source of electro-motive force.

Fig. 2 is a perspective view illustrating 40 the combined partition member and lamp-support detached or removed from the box or casing.

Fig. 3 is a vertical, longitudinal sectional view, the section being taken along the line 45 3—3 of Fig. 4.

Fig. 4 is a transverse vertical sectional view, the section being taken along the lines 4—4 of Figs. 3 and 10.

Fig. 5 is a diagrammatic view illustrating 50 the relation of the lamps to the angular partitions, and also showing the lamp-circuits in connection with the main circuit and switch-board.

Figs. 6 to 9, inclusive, are diagrammatic 55 views illustrating the effect of the lighted and non-lighted lamps in producing oppo-

sitely pointing arrows, portions of arrows and combination of arrows.

Fig. 10 is a fragmental, detail view illustrating one end of the box with its cover removed and one of the lamps on the main partition within the box.

Referring to these drawings in detail, in which similar reference characters correspond with similar parts throughout the 65 several views,

The device comprises a box 1 having a bottom 2 which is removably secured by means of U-shaped guides 3, the latter being preferably formed integrally with the front 70 and rear sides 4, as indicated in Figs. 1 and 4. The front and rear sides of the box 1 include transparent sign-figures or sign-surfaces. Although these sign-figures may be otherwise provided, they are provided, ac- 75 cording to the present disclosure, by fitting panes of glass 5 in the front and rear walls 4 and painting or otherwise depositing on portions of the glass an opaque material indicated at 6 in Fig. 3. The sign-surface or 80 sign-figure is represented by the clear portions of the panes 5, and each of these sign-figures represents two conventional arrows each of which has its head included in the feather-end of the other. The front ends of 85 the arrow-heads are outlined and defined by means of angular partitions 7, the points of the arrows terminating in the angles 8 of the partitions 7. The main partition 9 extends from end to end of the box or casing 1 and 90 divides the latter into front and rear sign-sections, and this main partition supports the angular partitions 7, being preferably integral therewith. By referring to Figs. 2 and 4, it will be seen that the angular parti- 95

tions are each slotted vertically to receive the main partition, the latter extending up into and terminating at the upper ends of the slots, as indicated at 10. In other words, the partitions 7 straddle the main partition 100 and are united therewith on opposite sides by any appropriate means. Moreover the main partition has lamp brackets or supporting sleeves 11 secured thereto by rivets or other appropriate means, and the lamps 105 12, which are supported thereby, shine into the front and rear partitions alike so that their rays pass out through the front and rear sign-figures.

The lamps 12 may be connected in parallel, 110 as indicated in Fig. 5, and in this figure a section of the main circuit is indicated at 13

and may receive its current from any appropriate source (not shown). A switch-board 14 is connected with the lamp circuits and may be supported at any appropriate and convenient portion of an automobile on which this device is installed. As shown in Fig. 5, the switches 15 are open so that the lamps are not lighted. Referring, however, to Fig. 6 it will be seen that the middle and left-hand lamps are lighted while the right-hand lamp is dark, and therefore, since the right-hand partition does not permit light to enter the right-hand compartment from the middle and left-hand compartments, the right-hand compartment is dark so that no light passes out through the windows at the right-hand compartment. The light which passes through the middle and left-hand portions of the windows presents to view the conventional representation of the arrow pointing rightward as indicated in Fig. 6. Similarly, as indicated in Fig. 7, the left-hand lamp being dark and the middle and right-hand lamps being lighted, the left-hand partition prevents light from entering the left-hand compartment from the middle compartment, and therefore, the device displays the conventional representation of an arrow pointing leftward as indicated in Fig. 7. When all three compartments are lighted as indicated in Fig. 8, each of the entire sign-surfaces or sign-figures is displayed in the form of two arrows having their stems and heads interlapped upon or merging with one another. On the other hand, if only the middle lamp is lighted, the double-headed arrow indicated in Fig. 9 is displayed. It is well-known that an arrow displayed on an automobile and pointing rightward indicates that the automobile is about to turn toward its right, and that if the arrow is pointing leftward, the automobile is about to turn to its left. In using this device, these facts of public knowledge are made use of as indicated in Figs. 6 and 7, and in addition, the sign shown in Fig. 8 can be displayed to indicate that the machine is going to stop and the sign illustrated in Fig. 9 can be displayed as a tail light or signal for indicating that the machine is standing.

Any appropriate wiring connections or circuits may be employed as indicated at 16 and these circuits may extend through the apertures 17 in the partitions 7.

A window 18 is provided in the bottom 2

so that the light may shine upon the number plate.

The casing 1, bottom 2 and partition member 9 are preferably formed of sheet metal with the exception of the non-metallic members previously mentioned.

Although I have described this embodiment of my invention specifically, it is not intended to limit this invention to these exact details of construction and arrangement, but changes may be made within the scope of the inventive ideas as implied and claimed.

What I claim is that my invention is:

1. A signal of the character described, comprising a housing having its forward and rear walls provided with openings, a sign carrying plate covering each opening and marked to provide a longitudinally extending indicator having a head at each end, transversely extending partitions positioned vertically in the housing and dividing the same into a central compartment and end compartments and at points intermediate their height off-set to intersect the heads of the indicators upon the cover plates, a partition carried by the transverse partitions and extending longitudinally of the housing in the upper portion thereof, and means for connecting lighting elements with the lower edge portion of the longitudinally extending partition for selectively lighting the central and end compartments of the housing.

2. A signal of the character described, comprising a housing having transparent plates in its forward and rear walls marked to provide indicating emblems, each having heads at its ends, partitions extending transversely through the housing to divide the same into separate compartments and intersecting the heads of the indicating emblems the partitions having slits leading from their upper ends, a longitudinally extending partition positioned in the housing and extending through the slits and supported by the transversely extending partitions, and means carried by the lower edge portion of the longitudinally extending partition for supporting illuminating elements beneath the longitudinally extending partition to light the forward and rear portions of the housing.

In testimony whereof I have hereunto set my hand.

CLARK H. LANDIS.
